UNITED STATES PATENT OFFICE.

HARRY T. JOHNSON, OF JERSEY CITY, NEW JERSEY.

DESIGN FOR A BINDING AND CONTACT POST FOR KNIFE-SWITCHES.

SPECIFICATION forming part of Design No. 32,190, dated February 6, 1900.

Application filed January 8, 1900. Serial No. 785. Term of patent 14 years.

To all whom it may concern:

Be it known that I, HARRY T. JOHNSON, a citizen of the United States, and a resident of Jersey City, Hudson county, New Jersey, ⁵ have invented and produced a new and original Design for a Binding and Contact Post for Knife-Switches, of which the following is a description, reference being had to the accompanying drawings, which form part of this ¹⁰ specification.

In the drawings, Figure 1 is a perspective view of a post embodying my invention, and Fig. 2 is a plan view thereof.

The design in its entirety consists of the ¹⁵ post having a base 1, which is carried upwardly and terminates at its upper end in the arms 2 and 3, having their opposing surfaces parallel, thus forming a flat-sided recess 4, extending across the upper part of the ²⁰ post. From the arm 2 is extended a plate 5, the inner surface of which is flat and is extended from the arm 2 in alinement with the

inner surface thereof. The plate 5 is offset at the lower portion of the recess 4 and is carried upwardly close to the arm 3 to the top of ²⁵ said arm, the plate thus forming a substantially parallel-sided recess 6 in continuation of the recess 4.

The leading feature of the design consists of the post having the recess extending diametrically across the same and the plate extended from the post and having its free end carried upwardly to form the recess in continuation of the recess in the post. ³⁰

Having thus described my invention, what ³⁵ I claim as new, and desire to secure by Letters Patent, is—

The design for a contact and binding post for a knife-switch herein shown and described.

HARRY T. JOHNSON.
